COMPOSITION SHINGLE AND ROOF
FORMED THEREWITH

Theophilus Gregory Murphy, Los Angeles, Calif.

Application July 29, 1940, Serial No. 348,321

12 Claims. (CL 108—7)

This invention relates to composition shingles and pertains more particularly to an "individual" composition shingle and the roof formed therewith.

5 A particular object of the invention is to provide an individual composition shingle of pleasing appearance and with enhanced wear characteristics.

10 A further object of the invention is to provide an improved composition shingle roof.

The "composition" material referred to herein is meant to include the material commonly used for roofing purposes.

15 It is the custom first to form a base sheet of felt which is made ordinarily of rag fibers or rag and asbestos fibers or the like, of the desired thickness and of sufficient porosity to permit it to absorb a molten waterproofing composition such as pitch, asphalt or the like, and of 20 sufficient strength to enable it to be manipulated during the operations of forming the ultimate roofing product. This is a common article of commerce which is ordinarily known as roofing felt and is produced on the usual paper-making 25 machines.

After the sheet has been properly saturated with the bituminous saturating compound, either by immersion in a bath of a molten bitumen or pitch, or by subjection to "pressure saturation," 30 the sheet is coated on one face with a fairly thin layer of high melting-point asphalt. For this purpose, oxidized or so-called blown asphalt is preferably employed because of its tough and rubbery nature. While the asphaltic coating is 35 still soft and plastic and before it has set, it is surfaced with any suitable form of crushed mineral such as crushed slate, tile or any other mineral grit which will impart the desired color and texture to the final product.

40 The grit is preferably formed in relatively large particles or granules which vary in form according to the material from which they are produced. The surface mineral coating is partially embedded in the plastic asphaltic coating 45 sufficiently to insure a firm interlocking of the granules with the asphaltic coating, but leaving the granules so exposed that the asphaltic layer is completely covered and masked by the particles or grains of grit.

50 The sheet thus formed, and ordinarily called mineral-surfaced or slate-surfaced roofing, is now cut into roofing elements which take the form of individual shingles. In general, all of the edges of such a shingle will expose the edge 55 of the felt and the asphalt layer. In laying a

roof according to my invention, as will subsequently be described in greater detail, the shingles will be laid in overlapping courses and in overlapping relation in each course in such manner that side and bottom edge portions of 5 the shingle will be exposed to the elements, this method of laying being commonly referred to as the "Dutch lap" method. Thus these exposed edge portions will be subject to mechanical stress and to the weather. The asphalt exposed 10 to the elements and to the sunlight is susceptible to rapid deterioration. This is especially true of the asphalt or other bitumen which is utilized as a saturating compound for the foundation 15 felt inasmuch as these films about the fibers of the felt are relatively thin. Due to the action of the light and of moisture, these films crumble; and this, together with the absorption of moisture by the exposed fibers, causes a breaking 20 down of the exposed edges and produces a tendency on the part of the exposed margin of the roofing element to curl. The curling is doubtless also accelerated by the fact that the layer of coating asphalt contracts under the influence 25 of the elements and the rays of the sun and because of oxidation to a greater extent than the saturated felt itself.

Another objectionable feature ordinarily encountered in composition shingle roofs laid by the Dutch lap method is that, when rain falls 30 on the roof, the water runs down over the surfaces of the shingles in close proximity to the exposed side edges of the overlapping side portions of adjacent shingles and tends to flow or 35 creep under these overlapping side portions and thus leak through the roof, and the leakage of water beneath these overlapping side edges is increased by the action of wind in blowing the water toward and under these overlapping side 40 edge portions.

The principal object of the present invention is to provide an improved composition shingle adapted for laying by the Dutch lap method, and an improved composition shingle roof laid by this method, in which the above-mentioned objectionable features are effectively overcome. In this connection, a particular object is to protect the body portion of the shingle (including the saturated sheet and its surface coating) from exposure to the deteriorating action of weather 45 and sunlight at the exposed side and bottom edges of the shingle. Another important object is to substantially prevent the leakage of water underneath the overlapping side edge portions 50 of the shingles.

A further object of the invention is to provide an individual composition shingle with its exposed edge portions enclosed in an asphaltic envelope.

5 Another object of the invention is to provide an improved shingle roof formed with individual composition shingles according to this invention, the roof being laid with a plurality of courses and being secured to the roof in such 10 manner that the fastening means is protected from the weather and the individual shingles are secured to one another.

A further object of the invention is to provide an improved roof using composition shingles 15 having thickened exposed marginal portions according to this invention, whereby the thickened portions act as gutters to conduct draining moisture away from the joints between shingles.

I accomplish the above and other objects of 20 the invention by enclosing the above-mentioned exposed edge portions and the marginal portions of the exposed side portions of an individual composition shingle in a continuous envelope of asphaltic material. To protect this envelope 25 from the action of the sunlight a layer of mineral granules, preferably of contrasting color to the surface coating of granules, is partially embedded therein.

My preferred shingle has an outline corresponding generally to a non-rectangular parallelogram, and, when laid in accordance with my preferred procedure, the exposed bottom edge portion extends substantially horizontally and the exposed lateral edge portion extends at an obtuse angle with respect to said bottom edge portion and thus at an angle to the path followed by rain and other liquids draining from the roof. The asphaltic envelope increases the thickness of the shingle at its exposed lateral marginal 40 portions and rises above the plane of the upper face of the shingle to form a wall which acts as a gutter to prevent liquids from draining over the lateral edge of the shingle into the joints between shingles, as will be described more fully hereinafter. When the shingles are shaped and laid in accordance with my preferred practice, the exposed lateral edge portions extend at an 45 angle to the path followed by liquids draining from the roof and the gutter action is further improved.

Further objects and advantages of my invention will be apparent as the description proceeds.

I have illustrated my invention in the accompanying drawings, in which:

Fig. 1 is a plan view of an individual composition shingle constructed according to this invention;

Fig. 2 is a sectional elevation of one of the 60 lateral edges thereof, taken along line 2—2 in Fig. 1;

Fig. 3 is a sectional elevation of the bottom edge thereof taken along line 3—3 in Fig. 1;

Fig. 4 is a sectional elevation of the equipment 65 which may be used to form a shingle according to my invention showing a shingle in different positions during the process in dot-dash lines;

Fig. 5 is a plan view of a shingle illustrating 70 the process of rolling the edges as viewed along line 5—5 in Fig. 4;

Fig. 6 is another view thereof taken along line 6—6 in Fig. 4;

Figs. 7 through 10 illustrate diagrammatically 75 the steps of shingling a roof according to the

"Dutch lap" method with shingles according to this invention.

Fig. 11 is a plan view of a portion of a roof laid in accordance with the principles described in connection with Figs. 7-10 and using shingles 5 according to this invention; and

Fig. 12 is a view partly in section and partly in elevation taken along line 12—12 in Fig. 11, illustrating the type of joint obtained when shingles are laid in accordance with this invention. 10

Referring to Figs. 1-3, an individual shingle according to this invention is shown to have an outline generally in the form of a non-rectangular parallelogram. The edges meet at obtuse 15 angles at diagonally opposite corners and at acute angles at the remaining corners. The shingle 10 may be constructed from common composition roofing material, as above described, which comprises a base layer 11 of rag or asbestos 20 roofing felt properly impregnated with asphalt or other commonly used waterproofing compound. The front face of the base layer 11 is provided with a thin layer 12 of higher melting point asphalt which bonds to the base layer 11 25 and acts as a matrix to hold a layer of roofing granules 12a.

Sides 13 and 14 of the shingle meet at an obtuse angle and, as will be explained more fully hereinafter, portions of these sides are exposed 30 when the shingle is laid in accordance with my preferred procedure. The exact obtuse angle used is not critical, but an angle of about 110° is satisfactory. Since the shingle has thickness, edges 13a and 14a, corresponding to sides 13 and 35 14 respectively, will of course be exposed to the weather for the same distance that the sides are exposed when the shingle is laid. Protection of these edges is of primary importance.

The exposed portion of lateral edge 13a of the 40 shingle (the shingle being shown in its common position for laying in Fig. 1) and the exposed portion of bottom edge 14a of the shingle are provided with coatings of asphalt or other suitable material as at 15 and 15a which are firmly 45 bonded with these edges and with the marginal portions of the front and rear faces of the shingle adjacent the sides 13 and 14, to form a continuous asphaltic envelope encasing the exposed side and bottom edge portions. The layers 50 or envelopes 15 and 15a are further provided with a coating of granules 16 and 16a respectively which are in turn bonded with the layers 15 and 15a respectively and are preferably partially embedded therein. Since the length of the 55 exposed lateral side is usually somewhat shorter than the length of the exposed bottom side, and for artistic reasons, I prefer to provide a wider marginal coating for the bottom side than for the lateral side, as may be seen by an inspection 60 of Figs. 1, 2, and 3.

In constructing shingles in accordance with this invention, they are ordinarily first cut in any convenient manner, as by means of machines provided for this purpose, from rolls of common 65 roofing material, since this material is readily obtainable. Although the exact size of the shingle may be varied over rather wide limits, I find a width of about one foot as measured between the top and bottom edges, and a length of about 70 one and one-half feet as measured along the bottom edge, suitable.

To form the reinforced edges of the shingles with the utmost convenience, a form of apparatus such as shown in Fig. 4 may be utilized. This 75

apparatus is shown as comprising a centrally disposed, longitudinally extending asphalt trough 20 provided with a suitable heat supply means such as burner 21 for maintaining the asphalt 5 in a molten or fluent state, the trough being maintained filled to a convenient height such as indicated by the dot-dash line 22 with molten asphaltic material. A pair of longitudinally extending troughs 23 and 24 are shown located 10 on opposite sides of the trough 20 and may extend for any suitable distance therealong. These troughs are adapted to hold quantities 25 and 26 of suitable granular mineral material.

Outwardly of these troughs are located work 15 tables 27 and 28 providing plane surfaces for supporting shingles during the operation of rolling the reinforced edge portions in a manner to be described subsequently. Obviously a single work 20 table and sand trough, when used in conjunction with the asphalt trough, is sufficient to practice this invention. However, it is preferable to construct the apparatus in the manner illustrated in 25 order to provide space for workmen on each side of the trough 22.

In practicing my invention, a blank for an individual shingle, either formed as described above or formed by other means, is first dipped with its lower or bottom edge, for example, to a desired 30 depth, say about five-eighths of an inch, below the surface 22 of the molten asphalt, which is maintained at a temperature of about 500° F. The shingle, indicated in dot-dash lines at 31a, is preferably maintained in a vertical position 35 during this step. After the shingle has remained in the position indicated at 31a for a few seconds so that the waterproofing material in the base layer 11 and the asphalt layer 12a will soften 40 and bond firmly with the coating formed by the asphalt in the tank 20, the shingle is then turned in the position indicated in dot-dash lines at 31b to dip the exposed side edge in the molten asphalt. The exposed lateral edge is preferably 45 impregnated for a shorter distance than the exposed bottom edge. For example, the lateral edge may be immersed to a depth of about one-quarter inch.

In order to maintain uniformity in the finished shingles, the trough 20 is preferably provided 50 with a shelf 32 having a central portion 33 which is located at a greater depth below the surface 22 than its outer portions 34 and 35. Thus when dipping the bottom edge of the shingle it is rested on the central portion 33 of the shelf, and when 55 dipping the lateral edge it is rested on one of the lateral edge portions such as the portion 34.

The position of the shingle during dipping of its lateral edge is preferably vertical as indicated in dot-dash lines at 31b. The lateral edge is 60 dipped for substantially the same length of time as the bottom edge, and the temperature of the molten asphalt is preferably substantially the same as the temperature of the asphalt in which the bottom edge was dipped.

After the dipping of both edges has been completed to form an envelope such as referred to in connection with Figs. 1-3, the shingle is then removed from the asphalt trough and first one and then the other of the coated edge portions 70 is inserted in the granule trough 23 in contact with the roofing granules 25 while the coating formed is soft and plastic. The shingle is preferably held vertically when in the granule trough, as indicated in dot-dash lines at 31c, and if any motion is imparted to the shingle this motion is 75

preferably away from the corner at which the coatings meet, so that if there is any tendency to shift the asphalt coating it is toward this meeting corner.

After dipping in the granules the shingle is 5 laid with its back face down against a flat surface such as afforded by the table 27, as indicated in full lines at 31d. The upper and outer faces of the reinforced edge portions are then subjected to a rolling operation to smooth these faces 10 and force the granules to partially embed in the 15 coatings.

A roller which I have found useful for this purpose is shown as comprising a pair of rollers 41 and 42 mounted with their axes substantially horizontal on a suitable frame member 43 which is provided with a handle portion 44. The roller is further provided with a third roll 45 which is mounted on the frame 43 with its axis generally 20 perpendicular to the axis of the rolls 41 and 42.

The bottom and lateral marginal portions of the shingle 31c which have been provided with the reinforcing coating are designated 46 and 47 respectively. The rollers 41 and 42 are adapted to press vertically downwardly on the upper 25 sides of these coated faces to firmly bond the roofing granules with this coating. The other roller 45 bears inwardly on the coating portion covering the edges. The roller is preferably given 30 a motion toward the meeting corner 48 of the two coatings. Thus the roller is applied in the direction of the arrow A on the lateral marginal portion 47 and in the direction of the arrow B on the bottom marginal portion. After thorough 35 rolling and after the coating has cooled sufficiently, the shingle is ready for use.

The above-described individual composition shingle is particularly adapted for shingling a roof in accordance with the "Dutch lap" method. This method is outlined diagrammatically in 40 Figs. 7-10. In these figures the numeral 60 designates the lower left-hand corner portion of a roof having a left side edge 61 and a lower edge 62. A first shingle 10a is laid in the lower left-hand corner of the roof. This shingle may be the same as the shingle 10 shown in Figs. 1-3, and is trimmed along its left side so that it will 45 lie with its bottom edge substantially along a horizontal line and parallel to the bottom edge 50 62 of the roof and with its left side edge parallel to the side edge 61 of the roof. The shingle 10a is secured in position by means of roofing nails 63 and 64 located in the upper left and lower right-hand corners of the shingle respectively.

A second shingle 10b is then laid overlapping the shingle 10a for a sufficient distance to cover the nail 64. Although the amount of overlap is largely a matter of choice, I have found that an overlap of approximately two inches for the sides of 60 shingles in a single course is satisfactory. The top and bottom edges of this shingle are aligned with the top and bottom edges of the shingle 10a. The shingle 10b is now secured in position by means of a roofing nail 65 in its upper left-hand corner which also passes through the portion of the shingle 10a lying below the shingle 65 10b. A roofing nail 66 is also placed in the lower right-hand corner of the shingle 10b.

A third shingle 10c is now laid overlapping the 70 shingle 10b in exactly the same manner that the shingle 10b was laid to overlap the shingle 10a. Shingle 10c is secured by means of roofing nails 67 and 68 in its diagonally opposite upper left-hand corner and lower right-hand corner as at 75

67 and 68. This process is continued until the lowermost course of shingles has been laid. A second course of shingles is now laid above the lower course in substantially the same manner 5 as the shingles are laid in the lower course. The second course is laid overlapping the first course by an amount which is about equal to the amount that the shingles overlap one another in the respective courses.

10 Referring now to Figs. 9 and 10, a first shingle 10d in the second course is trimmed in a manner comparable to the shingle 10a and is laid with its trimmed edge parallel to the edge 61 of the roof and with its right edge abutting and forming 15 a continuation of the left edge of the shingle 10b in the first course, and also with its top and bottom edges substantially parallel to the corresponding edges of the shingle 10a. The shingle 10b is held in place by means of roofing nails 71 and 72 located at its respective upper left-hand and lower right-hand corners.

The second shingle 10c in the second course is laid with its bottom edge forming a continuation of the bottom edge of the shingle 10d and overlapping 25 the shingle 10d by substantially the same amount as the shingle 10b overlaps the shingle 10a. The shingle 10e is held in place by means of roofing nails 73 and 74 in the diagonally opposite corners.

30 The third shingle 10f in the second course is laid in exactly the same manner as the shingle 10e and overlaps this shingle and is held in place by means of roofing nails 75 and 76. This process is continued till the second course is completed. Subsequent courses are added in the same manner until the roof is brought to its uppermost extremity at which point the roof is completed in accordance with common roofing practice. Suitable means such as strips of wood, 40 metal or composition material is usually provided along the side and bottom edges of the roof to hold the shingles firmly in position to prevent the entrance of moisture and to lessen the effects of the wind.

45 An inspection of Figs. 7-10 will show that each individual composition shingle is held in place by four roofing nails. For example, the shingle 10b is held in place by means of nails 65, 66, 67, and 74. It will also be noted that when the roof 50 is completed none of the nails are exposed to the weather since they are all covered by the shingles. In practice the surface occupied by the nails is covered with an adhesive cementing material which protects the nails from the weather and 55 also serves to hold down the lower left-hand corner of each of the shingles, as will be described more fully in connection with Figs. 11 and 12.

Referring to said figures, a portion of a roof 60 84 shingled in accordance with the method outlined in Figs. 7-10 is indicated at 79. The individual shingles 80 forming the roof may be constructed in the same manner as the shingle 10 illustrated in Figs. 1-3. Each of these shingles is provided with reinforced lateral and bottom 65 edge portions as indicated at 81 and 82 respectively, and the shingles are held to the roof by suitable means such as roofing nails 83 which extend through the shingles and into the roof 84. These nails may be applied in exactly the same 70 manner as the nails shown in Figs. 7-10.

After the shingles have been nailed in place the lower unsecured corner of each of the shingles is lifted and a layer of waterproof adhesive cementing material is placed beneath the 75 lower face of the shingle at this corner and be-

neth the marginal portions of the exposed lateral and bottom sides for a sufficient distance to cover the nails which lie beneath these sides. One of the shingles, indicated at 80a, is shown with its lower unsecured corner 85 lifted to show 6 how the layer of cementing material 86 is applied. After this layer 86 of adhesive cementing material is applied, the lower corner 85 of the shingle is pressed down against this layer to secure this shingle to the shingle beneath it and 10 to completely protect the nails from the weather.

The coated edge portions 81 and 82 of the shingle reinforce it and generally increase its mechanical strength, particularly they lessen the tendency of the shingle to rip along its edges. 15 At the same time the added weight and strength along the edges and the marginal portions of the front and rear faces along these sides reduce the tendency of the shingle to curl after it is applied. Coupled with this mechanical advantage, these 20 coatings protect the edges of the felted backing layer and prevent drying out of the waterproofing material and also lessen the tendency of the shingle to curl. This protective envelope also prevents the entrance of moisture into the edges 25 of the shingle. In this connection it should be pointed out that the coatings need not extend for the full length of the lateral and bottom edges and may be omitted on the portions of these edges which are overlapped by other shingles. 30

The reinforcing layer 81 extending along the lateral margin of the shingle performs an added function by virtue of the fact that it rises above the plane of the shingle, as may be seen by inspection of Fig. 12 and as indicated at 16 in 35 Fig. 2. In other words, the shingle is thickened along its lateral side. This layer acts as a gutter to prevent liquids from draining over the exposed lateral edge of the shingle and running into the upwardly extending overlapping 40 joints. In Fig. 11 a plurality of drainage lines are indicated at 87 and it will be seen that they all extend downwardly in a straight line until they reach the raised coated portion 82 which extends at an obtuse angle to the horizontal, at 45 which position they all converge into a stream 88 which runs along the gutter formed by this coating. Without the raised lateral edge portion, this liquid would tend to run over the lateral edge where it would be blown into, or otherwise 50 caused to penetrate, the overlapping side joint between the shingles and cause the roof to leak. Obviously, any liquid draining from the shingle to the left of the shingle displaying the drainage lines will drain away from the overlapping 55 joint.

Obviously my invention is subject to some modification, hence I do not choose to be limited to the above-described examples, but rather to the scope of the appended claims. 60

I claim:

1. As an article of manufacture, an individual composition shingle comprising: a sheet of composition roofing material having an asphaltic coating and a layer of partially embedded granular material on one face thereof, said sheet having an outline generally in the shape of a parallelogram with two of its sides meeting at one corner at an obtuse angle, said shingle being adapted for laying in accordance with the "Dutch lap" method whereby said corner and portions of said sides are exposed; and a reinforcing coating of granular material partially embedded in asphaltic material covering the exposed marginal portions of said sides. 75

2. An individual shingle adapted to be laid with others in overlapping courses so as to have exposed bottom and lateral edge portions, comprising a felted foundation impregnated with a waterproofing material; a coating of asphalt on the exposed face of said foundation; a layer of granular material attached to said coating; a continuous envelope of asphalt encasing said exposed bottom and side edge portions; and a layer of granular material partially embedded in said envelope of asphalt. 5
3. An individual shingle having an outline substantially of a parallelogram with two adjacent sides disposed at an obtuse angle, said shingle being adapted for laying with others in overlapping courses, whereby portions of said sides are exposed, said shingle comprising: a felted foundation impregnated with waterproofing material; a layer of asphalt on the top of said foundation as laid; a layer of granular material partially embedded in the top of said asphalt; another layer of asphalt extending along said exposed side portions and over a small part of the top and bottom faces of said foundation; and another layer of granular material partially embedded in said other asphalt layer. 10
4. An individual shingle of composition roofing material, having an outline substantially of a non-rectangular parallelogram with two adjacent sides disposed at an obtuse angle, said shingle having an additional coating of asphalt with a layer of granular material partially embedded therein, extending over the marginal portions of both faces of said shingle along said sides. 15
5. A shingle roof comprising: a plurality of individual composition shingles each having substantially the outline of a non-rectangular parallelogram, said shingles being laid in a plurality of substantially horizontally extending courses with each upper course overlapping a lower course, the shingles in each of said courses being laid with a corner at which the sides meet at an obtuse angle disposed toward the bottom and one side of the roof and overlapping the next shingle in that course located nearer to said side of the roof, each of said shingles being thickened at the exposed edge portions of said sides which meet an obtuse angle, whereby liquids draining from said shingle are guided by one of said thickened edge portions away from the adjacent overlapping joint. 20
6. A roof as set forth in claim 5, each of said shingles being secured to said roof by members extending through said shingle and into said roof and located near the corners of said shingle which meet at acute angles. 25
7. A roof as set forth in claim 5, the overlapping shingles in each course being secured to one another by a layer of cementing material located beneath said corner. 30
8. A roof as set forth in claim 5, the shingles in one course being laid with their lower edge overlapping the upper edge of shingles in the next lower course and with one side edge abutting the side edge of a shingle in said lower course. 35
9. A shingle roof comprising: a plurality of substantially horizontally extending shingle courses with each upper course overlapping a lower course, the shingles in each of said courses being laid progressively from one side of the roof to the other in overlapping relation, each of said shingles having substantially the outline of a non-rectangular parallelogram, the shingles in each of said courses being positioned with their corners at which their bottom and lateral sides meet at an obtuse angle disposed toward the bottom and said one side of the roof, the marginal portions of said lateral sides of said shingles being provided with a coating of asphaltic material having a layer of mineral granules partially embedded therein which rises above the front faces of the shingles, whereby liquids draining from a shingle are guided by said raised marginal portion away from the adjacent overlapping joint. 40
10. A roof as set forth in claim 9, each of said shingles being secured to said roof by members extending through said shingle and into said roof and located near the corners of said shingle which meet at acute angles. 45
11. A roof as set forth in claim 9, the overlapping shingles in each course being secured to one another by a layer of cementing material located beneath said corner. 50
12. A roof as set forth in claim 9, the shingles in one course being laid with their lower edge overlapping the upper edge of shingles in the next lower course and with one side edge abutting the side edge of a shingle in said lower course. 55

THEOPHILUS GREGORY MURPHY.
